UNITED STATES PATENT OFFICE

128,091

DESIGN FOR A SHOE

George H. Bingham, Jr., Cambridge, Mass., assignor to Cambridge Rubber Co., Cambridge, Mass., a corporation of Massachusetts

Application November 18, 1940, Serial No. 96,649

Term of patent 3½ years

To all whom it may concern:

Be it known that I, George H. Bingham, Jr., a citizen of the United States, residing at Cambridge, in the county of Middlesex and Commonwealth of Massachusetts, have invented a new, original, and ornamental Design for a Shoe, of which the following is a specification, reference being had to the accompanying drawing, forming a part thereof, in which:

The figure is a perspective view of a shoe showing my new design, the essential features

of which reside in the portion shown in full lines comprising the exposed sole edge extending around the forepart of the shoe and having the covering material slotted so as to reveal portions of an underlying surface, presenting an appearance contrasting in color with that of the covering material.

I claim:

The ornamental design for a shoe, substantially as shown and described.

GEORGE H. BINGHAM, JR.
